Primary Examiner — Katherine A Holbrow(74) *Attorney, Agent, or Firm* — Morgan, Lewis & Bockius LLP(57) **CLAIM**

The ornamental design for a computer display panel with graphical user interface, as shown and described.

DESCRIPTION

The FIGURE is a front view of a computer display panel with graphical user interface, showing our new design. The broken lines in the drawing represent portions of the computer display panel with graphical user interface that form no part of the claimed design.
